UNITED STATES PATENT OFFICE.

CHESTER F. JOHNSON, OF DETROIT, MICHIGAN.

CARBURETER.

1,244,858.

Specification of Letters Patent.

Patented Oct. 30, 1917.

Original application filed November 5, 1914, Serial No. 870,348. Divided and this application filed October 4, 1915. Serial No. 53,872.

To all whom it may concern:

Be it known that I, CHESTER F. JOHNSON, a citizen of the United States, and a resident of Detroit, in the county of Wayne 5 and State of Michigan, have invented a new and Improved Carbureter, of which the following is a specification.

This invention relates to carbureters, and some of its objects are to provide means 10 whereby a rich mixture may be supplied when starting and when it is desired to accelerate the engine for any purpose, and whereby the richness of the fuel mixture is reduced, when throttling down from high 15 speed, to that corresponding to economical running.

This invention consists in the details of construction shown, described and particularly pointed out in the claims, and the 20 present application is a division of my application for United States Letters Patent, Serial Number 870,348, filed November 5th, 1914 and resulting in Patent #1,166,595, January 4, 1916.

25 In the accompanying drawings, Figure 1 is a side elevation of one embodiment of my invention, parts being broken away to show the interior construction. Fig. 2 is a part-section part-elevation on the line 2-2 of 30 Fig. 3, the body of the carbureter being omitted. Fig. 3 is a plan view of the carbureter shown in Figs. 1 and 2, the throttle-spring being omitted.

In the embodiment of my invention 35 shown, the body 1 has formed therewith an upwardly extending neck 2 provided with the perforated flanges 3, through which bolts (not shown) may be inserted to attach the carbureter to the engine manifold 40 in the ordinary way. Also formed preferably integrally with the body is a laterally extending air intake 4 having an air valve 5 arranged to swing vertically on the pivot 6 carried by the lugs 7; said valve being normally held in engagement with the seat 8 by the spring 9, the tension of which may be regulated by turning the ribbed knob 10 about its axis. The details of this air intake, the air valve, and the valve controlling 45 means, form no part of the present invention but are disclosed and claimed in my United States Patent Number 1,095,212, of May 5th, 1914.

Clamped to the lower side of the body by

means of a series of screws 13 (but one of 55 which is shown), that are received in the threaded lugs 14 on the body, is a float chamber top 15 comprising a fuel inlet 16, a valve-seat 17 and a valve 18, the latter of which is controlled by the float 19 that 60 swings vertically about the pivot 20. The central portion of the top 15 is depressed as indicated at 23 and may be threaded to receive the nozzle 24 of the pipe 25, the latter of which extends downwardly and 65 is provided with fuel inlet openings 26; and the upper edge of the top 15 has formed therein one or more air inlet openings 27. Resting upon said upper edge and securely clamped between it and the body is the dia- 70 phragm 30, the central portion of which inclines downwardly and has projecting therethrough the upwardly flaring strangle tube 31 that surrounds the nozzle 24 and is perforated at 32 to allow any condensed 75 fuel to drip into the chamber surrounding the nozzle. The space between the body and the strangle tube constitutes the mixing chamber of the carbureter.

The float chamber top is preferably shouldered at 34 to receive the body 35 of the float chamber that may be clamped thereto by the thumb-screw 36, the threaded end 37 of which passes through a perforation in the lower side of the body 35 and engages 85 in the internally threaded lower end 38 of the pipe 25. Formed integrally with the body of the float chamber is a cylinder 40, the lower end of which is connected to the interior of the float chamber by a passage 90 41 (Fig. 2) of size sufficient to allow free movement of liquid from the cylinder to the float chamber or vice versa. The float chamber and the cylinder 40 together constitute 95 a fuel reservoir.

The cylinder 40 has sliding therein a piston, the construction of which may vary, but which is preferably formed of two pressed metal pieces: (1) the outer barrel 41' and lower end 42, the central portion of 100 which is depressed outwardly at 43; and (2) an inner barrel 44, the lower end of which is depressed inwardly at 45 and the upper end of which merges into the annular flange 46 that is soldered or otherwise secured to 105 the upper inner edge of the barrel 41'. Between the depressed portions of the ends of the inner and outer barrels is a ball 48 to

which is secured the piston rod 49. The latter passes upwardly through a relatively large hole 50 in a disk 51 that bears upon the upper end of the cylinder, and through 5 a hole of substantially its own diameter in the disk 52 that rests directly on the upper face of the disk 51. It will be seen that if the piston rod is given a swinging movement, the disk 52 will merely slide back 10 and forth on the disk 51, thereby preventing the escape of gasoline that may have leaked between the piston and the cylinder.

The disks are prevented from being raised from their proper positions by a cover that 15 comprises the top 54, in which an opening 55 is formed of substantially the same diameter as the opening in the disk 51, and a flange 56 that fits snugly around the outside of the cylinder. This flange is preferably provided 20 with a rib 57 in contact with the upper outer edge of the disk 51, and has also struck inwardly therefrom one or more tongues 58 (Fig. 2) which are received in the notches 59 that extend circumferentially of the cylinder 25 for a few degrees at intervals near its top. It is obvious that, by merely turning the cover around the axis of the cylinder, the tongues will be forced out of the notches, after which the cover may be removed. 30 Manifestly, other closures for the upper end of the cylinder than that just described may be used.

The threaded upper end 60 of the piston-rod 49 is received between the sections of 35 the correspondingly threaded, bifurcated end 61 of a connector 62; the ends of the sections being preferably joined by a clamping screw 63. Should it become desirable to change the depth of the stroke of the piston 40 into the cylinder, it is only necessary to loosen the clamping screw to allow the proper movement of the piston-rod in respect to the connector, after which the two last mentioned elements may again be securely clamped together in an obvious manner. The opposite end of the connector is pivoted at 65 to one arm 66 of a throttle lever that is rigidly secured to the throttle shaft 67 upon which the throttle valve 68 45 is mounted. Besides the arm 66, the throttle lever comprises the non-adjustable stop 69 and the adjustable stop 70 (so arranged as to engage opposite sides of an abutment 71 rigid with the neck 2) together with the actuating arm 72 from which an actuating rod 73 extends to a position within convenient reach of the user. The throttle valve 55 may be normally held in closed position by a tension spring 74 that extends from the arm 72 to any desired point, say pin 75 of the throttle valve controlling mechanism.

From the foregoing description the operation will be apparent:—The same force that holds the throttle valve normally closed 60 holds the piston in elevated position, and

consequently fuel flows freely into the lower end of the cylinder through the passage 41. The normal fuel level in the float chamber is slightly below the upper end of the nozzle 24, and as the throttle is opened, either for 70 the purpose of starting or for accelerating the engine, the piston is depressed and the fuel level in the float chamber is temporarily raised so as to cause an appreciable added amount to be discharged from the nozzle 75 and perhaps collect in the depression 23 whereby a rich mixture is fed to the engine. The reverse action is also true to a certain extent for, as the engine is being throttled down from high speed, the piston draws 80 fuel from the float chamber into the cylinder and thus reduces the flow from the nozzle, whereby a desirable lean mixture is produced. In case a single movement of the throttle valve from closed to open position 85 is insufficient to produce the desired quality of mixture for starting, it is only necessary to work the throttle valve back and forth a few times.

While I have shown the throttle valve in 90 the neck of the carburetor, it is obvious that it may be located elsewhere; for example, in the manifold of the engine. It is also clear that many other changes may be made in the details of construction without departing 95 from the spirit of my invention. I do not, therefore, wish to be limited otherwise than as indicated by the subjoined claims.

I claim:

1. A carburetor comprising a mixing 100 chamber, means for discharging fuel into the mixing chamber, a fuel chamber having a fuel admission valve and a float controlling said valve, a member arranged to be projected into the fuel chamber, and means for positively projecting the member into the chamber and for positively withdrawing it from the chamber, whereby the level of the liquid is temporarily raised or lowered in the chamber in which said float is contained as 110 desired to control the richness of the fuel mixture supplied by the carburetor.

2. A carburetor comprising a mixing chamber, a fuel passage for discharging fuel into the mixing chamber, a fuel chamber 115 having a fuel admission valve and a float controlling said valve, a throttle valve, manually operable means for controlling the throttle valve, a member arranged to be projected into the fuel chamber, and means for positively projecting the member into the chamber and for positively withdrawing it from the chamber, whereby the level of the liquid is temporarily raised or lowered in the chamber in which said float is contained as 120 desired to control the richness of the fuel mixture supplied by the carburetor, said last mentioned means providing a non-slipping connection between the member and the throttle-controlling means.

3. A carbureter comprising a mixing chamber, a fuel passage for discharging fuel into the mixing chamber, a fuel chamber having a fuel admission valve and a float controlling said valve, a throttle valve, manually operable means for controlling the throttle valve, a member arranged to be projected into the fuel chamber, and means for positively projecting the member into the chamber and for positively withdrawing it from the chamber, whereby the level of the liquid is immediately temporarily raised or lowered materially in the chamber in which said float is contained as desired to control the richness of the fuel mixture supplied by the carbureter, said last mentioned means including means for varying the relation between the throttle valve and the member which is projected into the fuel chamber.
4. A carbureter comprising a float chamber, a float for controlling the level of fuel therein, a mixing chamber, passage forming means for conducting fuel from said float chamber to said mixing chamber, a throttle valve, and means independent of the passage forming means for temporarily raising the level of fuel in the float chamber as the throttle valve is opened whereby an increased amount of liquid is caused to be temporarily delivered through said passage forming means to enrich the mixture.
5. A carbureter comprising a mixing chamber, a fuel passage for discharging fuel into the mixing chamber, a fuel chamber, means for normally maintaining the fuel in the passage at a predetermined level, a throttle valve, a manually operable throttle lever for controlling the valve, a member arranged to be projected into the fuel chamber, and adjustable means for connecting the lever to the member whereby a movement of the throttle lever in one direction is caused to project the member into the chamber and raise the level of the fuel in the passage, said adjustable means including a rod pivotally connected to the member, and a connector pivotally supported on the throttle lever and in engagement with said rod.
6. A carbureter comprising a mixing chamber, a fuel passage for discharging fuel into the mixing chamber, a fuel chamber, means for normally maintaining the fuel in the passage at a predetermined level, a throttle valve, a manually operable throttle lever for controlling the valve, a member arranged to be projected into the fuel chamber, and adjustable means for connecting the lever to the member whereby a movement of the throttle lever in one direction is caused to project the member into the chamber and raise the level of the fuel in the passage, said adjustable means including a threaded rod pivotally connected to the member, a connector pivotally connected to the throttle lever and having threads in engagement with the threads on the rod, and means for preventing rotation of the rod in respect to the connector.
7. A carbureter comprising a mixing chamber, a fuel passage for discharging fuel into the mixing chamber, a fuel chamber, means for normally maintaining the fuel in the passage at a predetermined level, a throttle valve, a manually operable throttle lever for controlling the valve, a member arranged to be projected into the fuel chamber, and adjustable means for connecting the lever to the member whereby a movement of the throttle lever in one direction is caused to project the member into the chamber and raise the level of the fuel in the passage, said adjustable means including a rod pivotally connected to the member, a bifurcated connector pivotally connected to the throttle lever, said rod passing between the bifurcations of the connector, and means for clamping the connector on the rod.
8. A carbureter comprising a mixing chamber, a fuel passage for discharging fuel into the mixing chamber, a fuel chamber, means for normally maintaining the fuel in the fuel chamber at a predetermined level, a throttle valve, a throttle lever for the valve, a piston arranged to be projected into the fuel chamber, and means for positively projecting the member into the chamber and for positively withdrawing it from the chamber, whereby the level of the liquid in the fuel chamber is temporarily raised or lowered as desired to control the richness of the fuel mixture supplied by the carbureter, said projecting means including a rod pivotally connected to the piston and a connector pivotally connected to the throttle lever, said connector and said rod being rigid with each other.
9. A carbureter comprising a mixing chamber, a fuel nozzle leading thereto, a fuel reservoir for supplying fuel to the nozzle, means tending to maintain fuel at a predetermined level in the fuel chamber, said fuel chamber including a cylinder, a piston arranged to be projected into the cylinder, two perforated members spaced from each other and closing the upper end of the cylinder, a perforated disk interposed between the members, a piston rod pivoted to the piston, said rod passing through the openings in the members and the perforation in the disk, and means for imparting a combined swinging and reciprocating movement to the piston rod, in which movement the piston rod slides through the perforated members and the perforated disk and the perforated members and disk together form a tight closure for the end of the cylinder.
10. A carbureter comprising a mixing chamber, a fuel nozzle leading thereto, a fuel reservoir for supplying fuel to the nozzle, means tending to maintain fuel at a pre-

terminated level in the fuel chamber, said fuel chamber including a cylinder, a piston arranged to be projected into the cylinder, a perforated member constituting a closure for 5 the upper end of the cylinder, a perforated disk conforming to and slidably transversely across the perforated member, a piston rod pivoted to the piston, said rod passing through the opening in the member and the 10 perforation in the disk whereby the piston rod is allowed both sliding and swinging movement and a seal is maintained for the upper end of the cylinder.

11. A carbureter comprising a mixing 15 chamber, a fuel nozzle leading thereto, a fuel reservoir for supplying fuel to the nozzle, means tending to maintain fuel at a predetermined level in the fuel chamber, said fuel chamber including a cylinder, a piston 20 arranged to be projected into the cylinder, a perforated disk resting on the upper end of the cylinder, a second perforated disk resting on and slidably across the first mentioned perforated disk, a perforated cover 25 inclosing both disks, a piston rod pivoted to the piston, said rod passing through the openings in the disks and the perforation in the cover whereby the piston rod is allowed both sliding and swinging movement 30 and a seal is maintained for the upper end of the cylinder.

12. A carbureter comprising a mixing 35 chamber, a fuel nozzle leading thereto, a fuel reservoir for supplying fuel to the nozzle, means tending to maintain fuel at a predetermined level in the fuel chamber, said fuel chamber including a cylinder, a piston arranged to be projected into the cylinder, a perforated member constituting a closure 40 for the upper end of the cylinder, a perforated disk conforming to and slidably transversely across the perforated member, a piston rod pivoted to the piston, said rod passing through the opening in the member 45 and the perforation in the disk whereby the piston rod is allowed both sliding and swinging movement and a seal is maintained for the upper end of the cylinder, and means for retaining the perforated 50 member in position on the cylinder against force applied longitudinally thereof, said retaining means allowing the member to be readily removed after being given a short angular movement about the cylinder.

13. A carbureter for hydro-carbon motors, comprising a mixing chamber, a fuel chamber, means for feeding fuel from said fuel chamber to said mixing chamber, said means comprising a float for normally maintaining the fuel in the fuel chamber at a predetermined level, and means in said chamber for materially varying the normal level of said fuel surrounding the float independently of the float and of the suction of the motor. 55

14. A carbureter for hydro-carbon motors, comprising a mixing chamber, a fuel chamber, means for feeding fuel from said fuel chamber to said mixing chamber, means for normally maintaining the fuel in said fuel chamber at a predetermined level, and means in said chamber for temporarily materially raising the level of fuel throughout the greater part of the surface area thereof independently of the means which 70 normally maintains the fuel at a predetermined level, whereby an increased flow of fuel to the mixing chamber is temporarily secured. 75

15. A carbureter comprising a mixing 80 chamber, means for discharging fuel into the mixing chamber, a float chamber, means for normally maintaining the fuel in the float chamber at a predetermined level, a throttle valve, means for manually controlling the throttle valve, a plunger constructed and arranged to be projected into said float chamber to materially raise the level of the fuel therein simultaneously with the opening movement of the throttle valve, whereby 85 an enriching of the fuel mixture is secured for a considerable period thereafter. 90

16. A carbureter comprising a float chamber having a cover with a cup shaped depression therein, a jet in communication 95 with the float chamber and opening into said depression, means for directing a thin current of air along the depression, a manually controlled throttle valve, a plunger projectible into the float chamber to materially 100 raise the level of the fuel therein as the throttle valve is opened, whereby the fuel is caused to overflow into said depression to form a richer mixture.

In testimony whereof I sign this specification. 105

CHESTER F. JOHNSON.
